3 Claims. (Cl. 24—33)

The invention relates to a conveyor-belt connection by means of V-shaped wire hooks connected by a transverse bridge.

The U.S. Patent 3,071,830 relates to a conveyor-belt connection by means of V-shaped double wire hooks; the limbs of which form an eye at one end and terminate at the other end in two angled claws which engage in the eye, when pressed in, there being auxiliary claws which are spaced from the angled claws and engage round the transverse bridge on being pressed in.

The present invention relates to an improvement of such a conveyor-belt connection and its purpose is to increase the strength of such connections. This is particularly important for belts of high-strength, synthetic fibres with strengths above 1000 kg. per cm. of belt width, because sufficiently high strength values could not be achieved in these belts with the wire-hook connections hitherto known.

In a conveyor-belt connection by means of V-shaped wire hooks, wherein the tips of one end of the limbs are bent round transverse bridge portions uniting the hooks into a row at the other ends of the limbs, the purpose of the invention is achieved as a result of the fact that each V-hook has on its clawless limb a transverse bridge portion which is formed by lateral bending and which bears against the neighbouring V-hook at such a short distance therefrom that the alternating eyes at the apices of the hooks lie close together laterally on the coupling pin.

One embodiment of the invention is illustrated by way of example and purely diagrammatically in FIGS. 1-4 of the accompanying drawings, in which:

FIGURE 1 is a side view of the wire hook according to the invention;

FIGURE 2 is a plan view of a row of hooks;

FIGURE 3 is a vertical section through a conveyor-belt connection according to the invention;

FIGURE 4 is a plan view corresponding to FIGURE 3;

Also, in the accompanying drawings,

FIGURE 5 is a plan view of a row of prior art hooks, and

FIGURE 6 is a plan view of a conveyor-belt connection formed of said prior art hooks.

The conveyor-belt connection consists of the two belt ends 1 and 2 and a coupling pin 3 which passes through the alternating eyes 21, 22 at the apices of the wire hooks 4, 5.

In the embodiment shown in the U.S. Patent No. 3,071,830, the individual V-shaped wire hooks are constructed in the form of double hooks, the limbs 11 of which, FIG. 5, are connected to one another by means of a transverse bar 12 which is welded on. The limbs 13 have long claws 14, which, when pressed in, engage, in the usual manner, round the transverse bridge portion

2

15 forming the eye of each double wire hook. Spaced apart from the claws 14 on the limbs 13 are welded auxiliary claws 16 which engage round the transverse bar 12 in the manner shown in FIGURE 6 after being pressed in.

In the hooks according to the invention, each V-shaped wire hook likewise has a shank or limb 33 with a long claw 34 and an auxiliary claw 36 which is welded on.

The clawless shank or limb of each V-hook lies generally in the same plane as shank 33. An intermediate portion 31a is slanted out of this plane and continued in an outer portion 31b parallel to said plane but spaced apart therefrom and terminating in a bridge portion 35 extending toward said plane and ending substantially within the same. The bridge portion bears against the neighbouring V-hook (FIGURE 2). The transverse bridge portions 35 may be welded to the adjacent hookless limbs 31. With a suitable formation of the bend, the welding may be omitted and the individual V-wire hooks in a strip of hooks are then held together only by a transverse rod 32 which is welded on.

In the conveyor-belt connection as shown in U.S. Patent No. 3,071,830, the spacing of the tips of the hooks in the belt amounts to 7 mm. With this spacing, a wire thickness of 2.4 mm. at the most can be selected without the spacing of the tips, which penetrate through, becoming irregular. This corresponds to a ratio of 1:2.92 of wire thickness to spacing.

As a result of the construction of the conveyor-belt connection according to the invention, it is possible for the transverse bridge portions 35 to bear against the adjacent V-hooks at such a short distance apart that the alternating eyes 21, 22 at the apices touch each other laterally on the coupling pin 3 (FIGURE 4). By this means, it is possible to reduce the ratio of wire strength to spacing to 1:2.2. As a result, not only are 25% more points available for the anchoring of the wire hooks in the ends of the belt but also the cross-section of the connection at the eyes 21, 22 of the hooks is likewise increased by 25%. Thus, with the conveyor-belt connection according to the invention, connections with greater strength can be produced in comparison with the so-called quadruplet hooks according to the U.S. Patent No. 3,071,830. With the embodiment illustrated, for example, the strength values can be increased by about 25%.

Having now particularly described my invention what I desire to secure by Letters Patent of the U.S. and what I claim is:

50. 1. A connector for a belt, said connector comprising a plurality of generally V-shaped connector elements, each of said elements having two shanks lying substantially in a common plane, one shank of each element terminating in a prong extending inwardly towards the other shank 55 and substantially lying in said common plane and said other shank having an inner portion lying within said plane, an intermediate portion extending out of said plane and an outer portion lying parallel to said plane but spaced apart therefrom and terminating in a bridge portion 60 extending toward said plane and ending substantially within the same, the pronged shanks of said elements being disposed side by side in parallel planes and the intermediate and outer shank portions of the other shank of each element being disposed on the same side of said planes 65 whereby said bridge portions all face in the same direc-

tion and define a substantially straight continuous line transverse of said planes.

2. A connector according to claim 1 wherein the tip of each of said bridge portions is fixedly secured to the next adjacent bridge portion.

3. A connector according to claim 1 wherein a cross bar extends across the outer portions of said other shanks and is fixedly secured thereto.
